[57] CLAIM

The ornamental design for a permanent make-up pigment applicator pen, as shown and described.

DESCRIPTION

FIG. 1 is a side and end perspective view of a permanent make-up pigment applicator pen showing my new design;

FIG. 2 is a side view;

FIG. 3 is an end view, enlarged relative to FIG. 1 and FIG. 2; and,

FIG. 4 is an end view, opposite that shown in FIG. 3. The broken line showing of the pen tip of FIGS. 1 and 2 is for purposes of illustration only and forms no part of the claimed design.

FIG. 1

FIG. 4
